(57) **CLAIM**

The ornamental design for a chair, as shown and described.

DESCRIPTION

FIG. 1 is a top, front, left perspective view of a chair with cover, showing our new design;

FIG. 2 is a front elevation view of the chair, showing the cover in an alternate configuration;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines shown along the edges of the cover represent stitching that do not form part of the claimed design. All other broken lines in the drawings illustrate portions of the chair that form no part of the claimed design.
